UNITED STATES PATENT OFFICE.

FREDERICK FREEMAN HOUSTON, OF CHICAGO, ILLINOIS.

CLAMP.

SPECIFICATION forming part of Letters Patent No. 357,387, dated February 8, 1887.

Application filed June 5, 1886. Serial No. 204,255. (No model.)

To all whom it may concern:

Be it known that I, FREDERICK FREEMAN HOUSTON, of Chicago, in the county of Cook and State of Illinois, have invented new and 5 Improved Clamps, of which the following is a full, clear, and exact description.

My invention relates to clamps adapted more especially for the use of carpenters, cabinet-makers, frame and box makers, and wood-10 workers in general, while clamping or gluing their work; and the invention has for its object to provide an efficient and durable device of this character.

The invention consists in certain novel features of construction and combinations of parts of the clamp, and in an arrangement of a series of clamps on a frame for effect on all four sides of framed work at once, all as hereinafter fully described and claimed.

Reference is to be had to the accompanying drawings, forming a part of this specification, in which similar letters of reference indicate corresponding parts in all the figures.

Figure 1 is a perspective view of a series of 25 my improved clamps arranged on a frame, partly broken away, and within which a piece of work—such as a picture-frame, sash, blind, or door—may be clamped. Fig. 2 is a side view of one of the clamps, showing the wedge-blocks as adjusted prior to clamping an object. Fig. 3 is a like view, but shows the wedge-blocks as adjusted for clamping the work. Fig. 4 is an edge view of one of the clamp-heads as applied to a clamp-bar carrying a 30 foot-block; and Fig. 5 is a sectional elevation through one of the clamps, taken on the line $x-x$, Fig. 2.

The clamp is made with two metal plates, A B, the opposing faces of which are bent or 40 flared at opposite end parts of the plates, as at $a-a$ and $b-b$, respectively, and from the ends of these parts $a-b$ flanges $a'-a'-b'-b'$ project about parallel with the bar C, to which the clamp is held in working position by metal grip-plates 45 D D and E E and bolts F G, as next described. The plates D D are laid at their one ends over the flanges $a'-a'$ of the clamp-plate A, and extend over opposite edges of the clamp-bar C. The bolt F is then passed through the plates 50 D D and the flanges $a'-a'$ at one face of the bar C, and is held to place by its nut f, and the

bolt G is passed through the opposite ends of the plates D D and at the other face of the clamp-bar C, and is held by its nut g.

The clamp-plate A is provided with an out-turned flange, a' , which lies flat against one face of the bar C, and the grip-plates D D are provided with shoulders $d-d$, which rest against the opposite face of the bar C, whereby the clamp is guided as it is shifted along the bar 55 60 into proper position to act on the work.

The grip-plates E E are shown as backward extensions of the flanges $b'-b'$ of the clamp-plate B, and these plates E have extremities e, which are bent over upon the back face of the 65 clamp-bar C, and aid the shoulders d of plates D in holding the clamp to and guiding it along the bar.

To the plates E E there is held by bolts or screws h the presser-block H of the clamp, 70 which block may consist of a short piece of wood fitted to the outer face of the bent clamp-plate B; or the presser may consist of a long sliding head block or bar, as at H', Fig. 1, held at opposite ends between the plates E E of 75 two clamps, which are held to clamp-bars C' C', which are fixed at their one ends to the opposite ends of a clamp-bar, C, and at their other ends are connected together by a cross-bar, C'. These bars C' H' C' C' constitute 80 a frame in which any piece of square or rectangular work may be clamped by two clamps holding the slide-bar H', and by two other clamps, one on each of the bars C' H', and as presently explained. The edges of the 85 clamp-bars C' H' C' C', on which the clamp-plates D E act, are faced with metal plates c, to prevent undue wear of the bars and provide for a firm hold of the clamps to the bars.

Between the opposing flared faces $a-b-a-b$ of 90 the clamp-plates A B there are placed opposite wedge-blocks, I J, which are held against the face of the clamp-bar by lips or lugs K on the plates A B, and through these wedges I J a headed bolt, L, is passed loosely, and is provided with a nut, M, outside of one of the wedges. I make the wedges I J preferably of a wood block, as at i j, covered at the edges by a metal frame or facing, as at i' j', to resist wear and promote durability.

To lugs n n on the back of the clamp-plate B 95 100 there are connected the extremities of a bent-

wire clip, N, to which is connected one end of a spiral spring, O, the other end of which is attached to the bolt F. The spring normally contracts and tends to draw the clamp-plates A B 5 toward each other. Any other form of spring having a like effect may be employed. When the nut M is unscrewed toward the extremity of the bolt L, the spring O, by drawing on the plates A B, separates the wedges I J, as in Fig. 2, and when the nut M is screwed onto or along the bolt L, when the bolts F G are tightened, the presser-block H or slide-bar H' will be forced forward against the work to be clamped.

15 The plate A is provided with suitable slots or openings, through which the spring O and the sides of the clip N may pass.

When frames or other objects having moldings or projections on their outer sides are to be clamped, removable blocks of like shape 20 may be interposed between the objects and the presser-blocks of the clamp.

The operation is as follows: We will suppose a square or rectangular piece of joined 25 work—such as a picture-frame—is to be held by the clamp-frame and clamps shown in Fig.

1. The nuts M of all the clamps will be unscrewed to allow separation of the clamp-wedges I J, and the clamps on the frame-bars 30 C² C³ will be slid along them to cause two opposite sides of the picture-frame to be held between the frame-bars C' H', whereupon the bolts F G of the clamps on the bars C² C³ will be tightened to hold these clamps against 35 back movement. The two clamps on the frame-bars C' H' then will be slid along the bars until the other two sides of the picture-frame are confined between the bar C' and the presser-blocks H H of these clamps. If, now,

40 the nuts M of all four clamps are tightened, the slide-bar H' and presser-blocks H H will be forced inward, and the picture-frame will be clamped at all four of its sides simultaneously, as will readily be understood. The

45 block H of the single clamp on the bar C in Fig. 4 will be pressed toward the foot-block H², fixed to the bar, when the nut M is tightened, to clamp work being glue-jointed or otherwise fastened between the blocks H H². It is obvious that the clamps thus may be used on a 50 bar-frame or on a single bar, and are adapted to clamp a large variety of work requiring joining or gluing in many branches of trade; but the clamps are designed more particularly

55 for wood-workers' use.

Having thus fully described my invention, I claim as new and desire to secure by Letters Patent—

1. The combination, in a clamp, of plates 60 A B, having opposing inclined faces, as at a b

a b, said plate A provided with means for binding it to a clamp-bar, and said bar and said plate B provided with a presser block or bar, wedges, as at I J, fitted between the plates A B, and a bolt, L, passed through the wedges 65 and provided with a nut, M, substantially as described, for the purposes set forth.

2. The combination, in a clamp, of a bar, as at C, plates A B, having opposing inclined faces a b, grip-plates D D, and bolts F G, 70 adapted to hold the plate A to bar C, grip-plates E, holding the plate B to bar C, wedges, as at I J, fitted between plates A B, and a bolt, L, passed through the wedges and provided with a nut, M, substantially as described, 75 for the purposes set forth.

3. The combination, in a clamp, of a bar, as at C, plates A B, having opposing inclined faces a b, grip-plates D D E E, and bolts F G, holding the plates A B to the bar C, elastic or 80 yielding connections—such as a clip, N, and spring O—arranged to draw the plates A B toward each other, wedges I J, fitted between plates A B, and a bolt, L, passed through the wedges and provided with a nut, M, substantially as described, 85 for the purposes set forth.

4. In combination, a clamp-bar, C, movable clamp-head H, held to the bar, a plate, A, having flanges a², grip-plates D D, having shoulders d, bolts F G in the plates D A, beveled blocks I J, interposed between the opposing beveled faces of the plate A and head H, and a device for drawing the blocks I J toward each other, substantially as described, for the 90 purposes set forth.

5. The combination, with a clamp-bar, as at C, a clamp-plate, A, held rigidly to the bar, a movable plate, B, opposite plate A, and adapted to hold a clamping-head, as at H; wedge-blocks I J, placed between plates A B, and a device for drawing the blocks I J toward each other, of block-retaining lips K on the plates A B, substantially as shown and described.

6. The combination, in a clamping device, 105 of a series of bars, C' H' C² C³ C', clamps comprising pairs of plates A B, wedge-blocks I J, interposed between the plates, and bolts and nuts L M, substantially as specified, said bar H' being attached to the plates B of opposite 110 clamps on the bars C² C³ to move with said plates, and said bars C' H' also carrying clamps having presser-blocks H H, adapted for movement toward the bar C', substantially as described, for the purposes set forth.
